Attnys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed July 23, 1925. Serial No. 45,270.

This invention aims to provide improvements in separable fasteners.

In the drawings, which illustrate a preferred embodiment of my invention:—

5 Figure 1 is an elevation view of the fastener as it appears when secured together;

Fig. 2 is a section on the line 2—2 of Fig. 1;

10 Fig. 3 is a section similar to Fig. 2, but showing the attaching prongs turned relative to the attaching plate during expansion of the stud-engaging part of the socket;

15 Fig. 4 is a section of the socket taken between the prongs to illustrate the manner in which the carrying fabric is gripped between the parts of the socket;

20 Figs. 5 and 6 include a plan and a side elevation of the resilient stud-engaging part of the socket; and

Fig. 7 is a section of a socket similar to that illustrated in Fig. 4, but showing the covering part of the cap removed.

25 Referring to the invention as illustrated in the drawings, I have shown a simple separable fastener having a stud member and a resilient stud-engaging part which are of the general type shown and more fully described in my co-pending application Serial No. 45,265, filed herewith.

30 The socket illustrated includes a ringlike stud-engaging part 1, split to permit contraction and expansion when the head of a stud is passed through the stud-receiving aperture 2. It also includes a prong-receiving attaching part or clinch plate 3, which 35 comprises a ringlike anvil part 4 generally curved in cross-section and covered by a separate cap member 5, as illustrated in Figs. 1 through 4. The cap member 5 may be 40 omitted if so desired (Fig. 7), being primarily a finishing part to cover the anvil part 4.

The attaching part 3 and stud-engaging part 1 are secured to opposite sides of a flexible fabric 6, which may be cloth, leather or the like, by a plurality of attaching prongs 7. These prongs are formed integral with the ringlike part 1 and pass through the fabric 6 whence they are bent curvilinearly inwardly and downwardly by the anvil part 4, as best illustrated in Fig. 2.

When the parts of the socket are secured together, the fabric 6 is gripped tightly between the upper edge 8 of the outer wall 9 of

the stud-engaging part 1 and the attaching part 3, as best illustrated in Figs. 4 and 7.

Attachment of the parts of the socket to the carrying fabric, by the means above described, permits the stud-receiving part and the prongs to expand and contract as a whole with but slight resistance on the part of the fabric or the clinch plate. Thus, when the head 10 of the stud 11 is entered in the stud-receiving aperture 2 (Fig. 3) the ringlike part 1 and the prongs expand as a whole in a generally lateral plane to permit the head 10 of the stud to pass into the ringlike part 1. The anvil part 4 provides a cam surface against which the curved portions of the prongs can slide a very slight but sufficient distance diagonally downward relative to the cap during engagement or disengagement of the socket with the stud, as illustrated in Figs. 2 and 3.

The stud may be secured to a flexible carrying medium 13 by a rivet 14, as described in the above-mentioned co-pending application.

The claims of this application are specific to the attachment of the parts wherein the upset portions of the prongs pivot in the attaching part. This structure differs from the other applications of applicant filed on the same date as this application, which show upset portions shiftable laterally relative to the attaching part or held rigidly by the attaching part. Therefore applicant has elected to claim in this application the novel structure shown and described without overlapping the claims of his other applications.

While I have shown and described a preferred embodiment of my invention, it will be understood that considerable changes may be made without departing from the scope of my invention, which is best defined in the appended claims.

Claims:

1. A snap fastener unit comprising a fastener element, a plurality of prongs presented by said element, said fastener element and prongs being adapted to yield laterally as a whole, and an attaching part presenting turning and clenching means against which the free ends of the prongs are upset to secure said fastener element to a support, the ends of said prongs being pivotally engaged with said turning and clench-

ing means to permit substantial free expansion and contraction of the fastener element as a whole.

2. A fastener socket including a resilient ringlike stud-engaging part, an attaching part located at the opposite side of a socket-carrying medium, and a plurality of attaching prongs presented by said ringlike part, said prongs being yieldable laterally with 5
10 said ringlike part, said prongs having their end portions passing through the carrying medium and bent downwardly by and into engagement with said attaching part to secure said parts to the carrying medium, said 15 downwardly bent portions adapted to swing as on a pivot within said attaching part thereby to permit free expansion of said ringlike part without interference from said prongs during engagement or disengagement 20 of said ringlike part with a stud.

3. A socket for a separable fastener including a resilient ringlike stud-engaging part, expandible and contractible as a whole, a cap member located at the opposite side of a flexible socket-carrying medium having 25 a generally curved prong-deflecting wall, and a plurality of attaching prongs formed integral with said ringlike part, said prongs passing through a support for said socket

and bent downwardly by the wall of said cap 30 to conform relatively closely to the curve of said wall, the ends of said curved portions of said prongs adapted to shift diagonally downwardly with relation to said curved wall during expansion of said ringlike stud- 35 engaging part thereby to permit the uncurved portions of said prongs to yield with said ringlike part.

4. A separable fastener installation comprising, in combination, a one-piece contractible and expansible fastener element, contractible and expansible as a whole, a flexible carrying medium, an attaching part located at the opposite side of the carrying medium from said fastener element, a generally curved 40 wall portion presented by said attaching part and a plurality of attaching prongs integral with the fastener element for securing said parts to the carrying medium, said prongs when engaged with said attaching part 45 adapted to pivot within said curved wall to aid in expansion of the fastener element for engagement or disengagement with a cooperating fastener part.

In testimony whereof, I have signed my 50 name to this specification.

FRED S. CARR.
